COMBINED GUM MASSAGER AND INTER-DENTAL STIMULATOR

Jack Diener, Washington, D.C.

Application August 28, 1959, Serial No. 57,358

Term of patent 14 years

(Cl. D24—1)

FIG. 1.

FIG. 2.

FIG. 3.

FIG. 4.

FIG. 5.

FIG. 6.

Fig. 1 is a top plan view of a combined gum massager and interdental stimulator showing my new design; and

Fig. 2 is a side elevational view thereof;

Fig. 3 is a bottom plan view thereof;

Fig. 4 is an enlarged fragmentary plan view of the stimulator end thereof, the broken line showing of the stimulator being omitted for convenience of illustration;

Fig. 5 is an enlarged cross-sectional view taken along line 5—5 of Fig. 1; and

Fig. 6 is an enlarged cross-sectional view taken along line 6—6 of Fig. 1.

The dominant features of my design reside in the full line portions of the drawing.

I claim:

The ornamental design for a combined gum massager and interdental stimulator, as shown and described.
